UNITED STATES PATENT OFFICE.

ISRAEL HENRY MOSS, OF CINCINNATI, OHIO.

DESIGN FOR SAD-IRON.

Specification forming part of Design No. 6,146, dated September 17, 1872.

To all whom it may concern:

Be it known that I, ISRAEL HENRY MOSS, of Cincinnati, Hamilton county, Ohio, have invented a certain new and original Design for a "Sad-Iron," of which the following is a specification:

The accompanying drawing is an elevation of a sad-iron embodying my design.

The first part of my design relates to the sad-iron body A, having moldings B B', of corresponding shape and proportions, around its top and bottom edges. The opening C is also provided with a marginal molding, D. The second part of my invention relates to the shape of the handle, which consists essentially of the handle proper E, the shanks e e', and guard or heat deflector F, all of the aforesaid members being cast in one piece and of the form represented.

Claims.

I claim as my invention—

1. The design for the sad-iron, as shown at A B B' D.
2. The design for the handle of the sad-iron, as shown at E e e' F.

In testimony of which invention I hereunto set my hand.

ISRAEL HENRY MOSS.
